The ornamental design for a container for a snack food kit, as shown and described.

DESCRIPTION

FIG. 1 is perspective view of a container for a snack food kit; FIG. 2 is a rear elevational view of the container of FIG. 1; FIG. 3 is a front elevational view of the container of FIG. 1; FIG. 4 is a top plan view thereof; FIG. 5 is a bottom plan view thereof; FIG. 6 is a left side elevational view thereof; and, FIG. 7 is a right side elevational view thereof.

The ornamental design which is claimed is shown in solid lines in the drawings. The broken lines shown in the drawings are perforations, and also form part of the claimed design.
